UNITED STATES PATENT OFFICE.

CHARLES E. ROBERTS, OF OAK PARK, ASSIGNOR TO THE NATIONAL CUTLERY COMPANY, OF ROCKFORD, ILLINOIS.

MACHINE FOR GRINDING HANDLES OF TABLE-KNIVES.

SPECIFICATION forming part of Letters Patent No. 554,797, dated February 18, 1896.

Application filed February 11, 1895. Serial No. 538,039. (No model.)

To all whom it may concern:

Be it known that I, CHARLES E. ROBERTS, a citizen of the United States, residing at Oak Park, in the county of Cook and State of Illinois, have invented a new and useful Improvement in Machines for Grinding Handles of Table-Knives, of which the following is a specification.

This invention relates to improvements in machines for grinding the handles of table-knives.

The nature of the invention is fully set forth below and illustrated in the accompanying drawings, in which—

Figure 1 is a plan of the machine; and Figs. 2, 3, and 4 are sectional views on the lines 2 2, 3 3, and 4 4, respectively. Fig. 5 is a longitudinal section of the chuck.

In said drawings, A represents a suitable grinding-wheel journaled in the bearing A' and driven by the pulley A². The bearing is supported upon pivoted standards A³, which are controlled by a screw A⁴ and a spring A⁵, this construction permitting the bearing to be adjusted toward the work as the wheel becomes reduced in diameter.

The knife-blank shown at W is held at one end in a rotating chuck or head B, supported in a head-stock B', and at the other end by a rotating center C, held in a tail-stock C', and both the chuck and center stock are mounted upon a carriage D, which is capable of a longitudinal movement to carry the handle from end to end past the grinder, and also of a rocking motion, so that the blank may be moved toward and away from the wheel and thus allow for the oval shape of the cross-section of the handle.

The chuck B is provided with rocking clamping-arms B², which are adapted to grasp the bolster portion of the blank upon the broader sides thereof, and are forced into action by the sliding stepped cone B³, which enters between the rear ends of the arms and spreads them. The cone is moved forward in this operation by the hand-lever B⁴ and the pivoted yoke B⁵ connecting the lever with the cone and having trunnions B⁶ working in a groove B⁷ in the cone. (The cone is loose upon the shaft of the chuck.) Rotary mo-

tion is communicated to this chuck by the pulley B⁸ and belt B⁹ from the pulley G.

The other end of the knife-blank carries a tang V, formed upon the outer end of the handle at the time the blank is forged, and this tang is inserted in the rotatable centering device C. The center is movable in both directions by a rocking cam C⁴, operated by a hand-lever C⁵. The lever enables the operator to apply considerable power when that is necessary to insure a firm seating of the tang in the center. The center is encircled by a sleeve C⁶, in which it has freedom to rotate and which moves with it in its longitudinal movements. The spring C² and pin C³ press against the outer end of the center and thus serve to counteract any tendency by the hand-lever to turn the cam by gravity.

Both the head-stock and the tail-stock are supported upon the carriage D, as is also the yoke B⁵. An outer bearing B¹⁰ is provided for the shaft of the chuck and its pulley, and such bearing is also supported upon the carriage. The carriage is itself supported and both slides and rocks upon a stationary shaft E, sustained in a wide bearing E' upon the main frame. Bushings E² encircle the shaft at the points where the carriage is joined to it. The rocking of the carriage permits the blank-holding device to be moved toward or away from the grinding-wheel, so that the grinding may impart the oval shape desired for the handle. This rocking movement is caused by the contact of the rotating form F, also journaled upon the carriage and rotated by the gears F' F², the latter upon the journal of the chuck, with the stationary roller F³ supported upon a standard F⁴. The carriage is maintained in position with the form in constant contact with the roller by spring-pressure caused by the spring F⁵ encircling the stem of and acting upwardly upon a plunger F⁶ carrying an antifriction-roller F⁷ against a projecting arm F⁸ upon the side of the carriage opposite to that upon which the form is located.

The sliding or longitudinal movement of the chuck-carriage is caused by the following mechanism: The pulley G, already mentioned, from which power is carried to the chuck-

pulley, is attached to and moves with another pulley, G', and both are loosely supported upon a shaft H. Secured in the web of pulley G' is a stub-shaft or pivot H', upon which are 5 rotatably mounted two pinions H² H³, secured together or made in one piece so as to move together. Of these pinions that lettered H² meshes with a stationary or non-rotating gear H⁴ secured to the frame of the machine, while 10 pinion H³ meshes with a gear H⁵ splined upon shaft H. The gears H⁴ and H⁵ are of the same diameter, but the former has a tooth or two more than the latter. From this construction 15 it will be seen that by the rotation of the pulley G' the pinions are carried around the gears, and as one of the latter is stationary the pinions are necessarily rotated, and thereby motion is transmitted to gear H⁵ to the extent of the difference in the number of teeth 20 in the gears—that is to say, gear H⁵ will be actuated each time the pinions travel around it the distance or space of one tooth or other number of teeth which said gear possesses over gear H⁴. This causes a very slow rotation 25 of shaft H, which I utilize as a means whereby to obtain the sliding movements of the carriage by providing the shaft with a peripheral cam H⁶ and the carriage with the antifriction-roller H⁷, adapted to be engaged 30 by such cam. The return movements of the carriage are caused by a weight J, which also keeps the roller normally in contact with the cam.

The machine is adapted to polish all of the 35 handle of the knife except the rounded outer end, and its operation will be fully understood from what has already been given in the above description.

I claim—

- 40 1. The combination in a cutlery-grinding machine of a grinding-wheel, a rotating chuck B movable pressure-exerting levers, means for throwing said levers into action, and a centering device C, adapted both to rotate 45 and to slide, and a rocking cam for sliding it away from the knife-blank, and a spring for keeping it in action, substantially as specified.
2. The combination with the blank-holding devices and their sliding carriage, of the cam 50 for actuating the carriage in its sliding movement, and the gearing for turning the cam, said gearing consisting of pinions H' H² and differential gears H⁴ H⁵, one of the latter being stationary, substantially as specified.

3. The combination with the carriage and 55 the cam for sliding it, of pulley G', pinions H' H² and differential gears H⁴ H⁵, one of the latter being splined to the cam-shaft and the other being held stationary, substantially as specified. 60

4. The combination of the rotary blank-holding devices and the sliding carriage upon which said devices are mounted, with the shaft E supporting the carriage and upon which it rocks, and means for sliding the carriage upon the shaft, substantially as specified. 65

5. The combination of the rotary blank-holding devices and the sliding carriage upon which said devices are mounted, with the 70 shaft E supporting the carriage and upon which it rocks, means for sliding the carriage upon the shaft, and the form and opposing spring for rocking the carriage, substantially as specified. 75

6. The combination with a rotating chuck, a rotating form located alongside the chuck, and a rocking and sliding carriage upon which both chuck and form are supported, of a stationary roller bearing against the form in any position of the carriage and a spring device acting upon the carriage and serving to keep the form against the roller, substantially as specified. 80

7. The combination with a rotating chuck, 85 a rotating form, located at the side of the chuck, and a rocking carriage upon which both chuck and form are supported, of means for rotating the chuck and form at a similar speed, a stationary roller bearing against the 90 form, and a spring device acting upon the carriage and serving to keep the form against the roller, substantially as specified.

8. The combination with a rotating chuck, 95 a rotating form at the side of the chuck, intermeshing gears upon the chuck and form, and a rocking carriage upon which both chuck and form are supported, of a stationary roller bearing against the form, and a spring device 100 acting upon the carriage and serving to keep the form against the roller, substantially as specified.

CHARLES E. ROBERTS.
